UNITED STATES PATENT OFFICE.

EZRA HOLLIS, OF OILFIELD, ILLINOIS, ASSIGNOR OF ONE-HALF TO T. M. FOUST, OF OILFIELD, ILLINOIS.

CORN-HUSKING MACHINE.

1,116,278.

Specification of Letters Patent. Patented Nov. 3, 1914.

Application filed May 11, 1914. Serial No. 37,931.

To all whom it may concern:

Be it known that I, EZRA HOLLIS, a citizen of the United States, residing at Oilfield, in the county of Clark and State of Illinois, have invented certain new and useful Improvements in Corn-Husking Machines; and I do declare the following to be a full, clear, and exact description of the invention, such as will enable others skilled in the art to which it appertains to make and use the same.

This invention relates to new and useful improvements in corn harvesters and more particularly to a corn husking machine and the primary object of the invention is to provide an improved device of this character which snaps the ears from the stalks and carrying the same to a predetermined point removes the shucks therefrom and conveys the clean ears to a predetermined point on the machine.

Still another object of the invention resides in providing improved husking and ear removing rolls on the machine and a still further object resides in providing an improved construction for coöperation with said rolls whereby to convey the ears of corn to various parts of the machine.

A still further object resides in providing a device which is simple and durable in construction, comparatively inexpensive to manufacture and one which will be very efficient in use.

With these and other objects in view my invention consists of the novel features of construction, combination and arrangement of parts as will be hereinafter referred to and more particularly pointed out in the specification and claim.

40 In the accompanying drawings forming a part of this application: Figure 1 is a plan view of the device constructed in accordance with my invention. Fig. 2 is a side elevation thereof with parts broken away to disclose the relation of the snapping rolls to the endless carriers arranged on opposite sides thereof. Fig. 3 is a rear elevation of the device. Fig. 4 is a transverse section through the device as seen on line 4-4, Fig. 1 looking in the direction of the arrow. Fig. 5 is a similar view as seen on line 5-5, Fig. 1, looking in the direction of the arrow. Fig. 6 is a horizontal section as seen on line 6-6. Fig. 7 is a vertical transverse section as seen on line 7-7, Fig. 5.

In describing the invention I shall refer to the drawings in which similar reference characters designate corresponding parts throughout the several views and in which 1 indicates a frame such as is usually provided on devices of this character, the same being operatively mounted on the supporting wheels 2. Mounted on the side of the frame 1 about midway of the ends thereof are the uprights 3 which are connected at 60 their upper ends and together form a supporting frame 4 for various operating parts of the device as will be hereinafter set forth.

Arranged in the rear portion of the frame 1 is a platform 5 upon which is mounted a motor 6 which is designed for the operation of various parts of the device as will be also hereinafter set forth. The crank shaft 7 of this motor has an enlarged sprocket 8 mounted thereon over which is trained a chain 9 the latter being also trained over a sprocket 10 carried on the outer end of a rotatable shaft 11 which is mounted in the side bars 3 of the supporting frame 4. This shaft 11 forms the main driven shaft for the operating parts of the device and with the same all other operating parts coöperate.

The forward portion of the frame or base 1 is slotted about centrally, the forward portion of the slot being flared as indicated at 12 such design being the usual design for devices of this character and mounted adjacent the forward end of said frame 1 and directed upwardly and rearwardly are the side bars of a frame 13, the upper ends of said side bars being mounted in the upper connecting bar of the frame 4 whereby to form a perfect support therefor. Journaled in bearings 14 mounted on the base or frame 1 on each side of the slotted portion thereof adjacent the forward end are the trunnions of the forward or outer ends of a pair of snapping rolls 15, the trunnions at the opposite or upper ends of said rolls being rotatably mounted in a bearing bar 16 carried on the upper portion of the frame 4. These rolls 15 contact with one another as is usual in devices of this character, the same being provided with spiral corrugations indicated as 17 and these corrugated portions mesh with one another in the rotation of these rolls.

The trunnions at the rear or upper end of said rolls 15 project entirely through the bearing bar 16 and are provided with bevel 110

gears 18 which mesh with additional bevel gears 19 carried on a rotatable shaft 20. This shaft 20 is rotatably mounted in the side bars of the frame 4 adjacent the upper end of the same, one end thereof projecting beyond one side bar of said frame and having a sprocket 21 thereon. This sprocket connects with an additional sprocket 22 through the medium of a chain 23 said sprocket 22 being carried on the adjacent end of an additional rotatable shaft 24 mounted between the side bars of said frame 4 just below the shaft 20. The shaft 24 which is mounted just below the shaft 20 is disposed just above the main driven shaft 11 and the end of the shaft 24 opposite that carrying the sprocket 22 is provided with a pinion 25 meshing with a pinion 26 carried on the adjacent end of said shaft 11. Thus when said shaft 11 is caused to rotate from the operation of the motor 6, the rolls 15 will be rotated inwardly toward one another through the various connections hereabove described and clearly shown in the Fig. 1 of the drawings. These rolls 15 are obviously for the purpose of snapping the ears of corn from the stalks as this machine is propelled through the field and carriers are provided in connection with the forward portion of the machine for conveying the ears of corn upwardly to husking rolls after said ears have been removed from the stalks. In carrying out this idea I, therefore, provide a pair of endless carriers 27, one being disposed on each side of the pair of rolls 15 and within the frame formed by the bars or plates 13. The lower ends of these carriers are trained over idle rollers 28 rotatably mounted on the frame 1 adjacent its forward end while the upper portions of said carriers have the guiding portions thereof suitably trained over driving sprockets 29 carried on the shaft 24. Thus it will be seen that as the ears of corn are snapped from the stalks, the same will be thrown to the conveyers 27 which carry said ears upwardly and direct the same to a husking mechanism to be hereinafter and more particularly set forth.

50 A gathering mechanism is also provided for the stalks from which the ears are removed and to this end, inwardly projecting stub shafts 30 are provided on the frame 4 the same being supported in position by means of the braces or bearing bars 31. A pair of such shafts 30 are provided each having a pinion 32 which meshes with a similar pinion 33 carried on the shaft 11 arranged thereabove and thus said stub shafts are caused to rotate upon the rotation of the shaft 11. The inner opposed ends of said stub shafts 30 are provided with sprockets 34 over which are trained the endless chains 35. These chains are provided with prongs or the like 36 and said chains

are trained at their lower ends over sprockets 37 which are mounted on vertical axes on said frame or base 1. It is obvious from this construction that the stalks from which the ears are removed by means of the snapping rolls 15, may be gathered as the device is propelled through the field.

Secured to the upper portion of the frame 4 and projecting rearwardly and downwardly therefrom are the side bars 38 of what may be termed a rear projecting frame or the like. Arranged between the side bars of this frame and inclined in the same plane therewith are the pairs of husking rolls 39, there being two pairs thereof spaced one from the other, the rolls of each pair are, however, in abutting relation to one another and are provided with spiral corrugations as indicated at 40, similar to the spiral corrugations of the rolls 15. The ears of corn are deposited on these rolls from the conveyers or carriers 27 and the spiral corrugations 40 of said rolls 39 which mesh one with the other engage the husks of the ears and remove said husks therefrom, permitting the ears to roll downwardly to the extreme rear portion of the device from which point the same are conveyed to a predetermined point as will be hereinafter and more particularly set forth. These rolls 39 have the stub shafts at the lower or rear end thereof rotatably mounted in journals 41 and the upper or forward trunnions of said pairs of rolls are provided with bevel gears 42 meshing with similar bevel gears 43 carried on the rotatable shaft 11 above referred to. These pairs of rolls 39 are thus seen to be rotated directly from the main driven shaft 11 and said pairs of rolls 39 are separated by means of a concavo-convex partition plate 44 as clearly shown in Figs. 1 and 3 of the drawings.

As stated above, the ears of corn from which the husks are removed are directed downwardly toward the rear end of the device and from this point the same are conveyed to a receptacle such as a wagon box arranged at a predetermined point with respect to the base or frame 1 and this last referred to conveying means is through the medium of a transversely arranged conveyer. In carrying out this idea, a transversely arranged conveyer frame 45 is provided the outer portion of which projects considerably beyond one side of the frame 1 and is directed upwardly as indicated at 46. A horizontal but transversely extending conveyer 47 is operatively mounted in the frame 45, the same extending over rollers carried on shafts 48 and 49. These shafts are mounted in bearings 50 on the frame 1 and project through the sides of the frame 45. Arranged in the upwardly projecting portion 46 of the conveyer frame is an additional conveyer 51 which is designed for coop

ation with the conveyer 47 and this conveyer 51 extends over rollers carried on shafts 52 and 53 respectively. The shaft 52 at the lower end of the upwardly inclined conveyer 51 and the outer shaft 49 of the conveyer 47 each has one end thereof projected beyond the conveyer frame 45 and the same are respectively provided with sprockets 54 and 55 over which is trained a chain 56. In this 10 manner the outer section 51 of this conveyer is caused to operate upon the operation of the inner section 47 of the conveyer, the sections operating in the same direction so that the contents of the inner section will 15 be disposed onto the outer section whereby the latter may direct the same to the receptacle provided for the reception of the ears of corn after the shucks have been removed therefrom.

20 Mounted transversely of the frame 1 in bearings immediately adjacent the lower and rear ends of the husking rolls is a rotatable shaft 50' and one end of this shaft is adapted to be connected with the main 25 drive shaft 11 by means of a linked chain 51' the same being trained over a sprocket 52' on the main drive shaft and a sprocket 53' on said shaft 50'. This shaft 50' is provided with bevel gears 54' at suitable 30 points thereon which connect with additional bevel gears 55' carried on the trunnions of the rollers over which are trained the reaches of the inner section of the conveyer 47. It will be obvious from this construction 35 that the sections of this conveyer 47 are operated upon the rotation of said shaft 50' which latter shaft is rotated directly by the main drive shaft 11.

Connected to the forward portion of the 40 frame or base 1 are the draft attaching devices 57 whereby it will be seen that the device may be propelled through a field, it not being my desire to propel this device from the motor described and shown. It 45 will thus be seen from this construction should the draft devices be halted for any reason whatsoever, this will not interfere with the operation of the motor and the parts connected therewith. The operating 50 parts of the machine may, therefore, be entirely cleared or cleaned of their contents

when the device is halted and there will be no clogging of the operating parts as is true with devices wherein the propulsion of the device is necessary with the operation of the actuating parts. The advantage 55 of such a construction appears obvious. I have also provided an operating lever 58 at the forward portion of the frame or base 1 whereby the latter may be tilted to various 60 positions as desired in the operation thereof.

From the foregoing description of the construction of my improved device the manner of applying the same to use and the operation thereof will be readily understood 65 and it will be seen that I have provided a simple, inexpensive and efficient means for carrying out the objects of the invention.

While I have particularly described the 70 elements best adapted to perform the functions set forth, it is obvious that various changes in form, proportion and in the minor details of construction may be resorted to, within the scope of the appended 75 claim, without departing from the spirit or sacrificing any of the principles of the invention.

Having thus described my invention what I claim is:—

In a corn husking machine, the combination with a frame and mechanism thereon for removing ears of corn from the stalks; of means for conducting the stalks to points out of engagement with the operating portions of the machine including a pair of spaced apart sprockets mounted on the frame on horizontal axes, an additional pair of spaced sprockets also mounted on the frame in a plane below the aforesaid sprockets and on vertical axes, a pair of endless chains each twisted and trained over an upper and a lower sprocket, and prongs carried on said chains to engage the stalks.

In testimony whereof I have hereunto set 95 my hand in presence of two subscribing witnesses.

EZRA HOLLIS.
